UNITED STATES PATENT OFFICE.

BENJAMIN R. TURNER AND ROBERT L. HIGGINBOTHAM, OF NORFOLK, VIRGINIA,
ASSIGNORS OF TWO-EIGHTHS TO C. S. ABELL, OF NORFOLK, VIRGINIA.

AUTOMATIC METAL FEEDER.

Application filed October 14, 1924. Serial No. 743,619.

To all whom it may concern:
Be it known that we, BENJAMIN R. TURNER and ROBERT L. HIGGINBOTHAM, citizens of the United States, residing at Norfolk, in the county of Norfolk and State of Virginia, have invented certain new and useful improvements in Automatic Metal Feeders, of which the following is a specification, reference being had therein to the accompanying drawing.

The present invention relates to automatic feeders for melting pots, especially those used on typecasting machines, and the invention aims to provide an automatic feeding device which is simple in construction and operation, convenient to install, and efficient in operation.

Another object is the provision of an automatic feeder of the kind indicated wherein the metal is delivered in solid form into the molten metal to be melted by contact with the molten metal, with means to automatically control the feeding of the solid metal into the pot, and the solid metal being supported from the frame of the machine so as to relieve the pot of excessive weight and strain.

A further object is the provision of such a device comprising a novel construction and arrangement of the component elements to enhance the utility and efficiency of the device.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a side elevation of the improved device as installed, showing the metal melting pot and other portions in section.

Fig. 2 is a vertical section on the line 2—2 of Fig. 1.

Fig. 3 is a horizontal section on the line 3—3 of Fig. 1.

Fig. 4 is a fragmentary plan view of the adjustable supporting means.

Fig. 5 is a sectional detail on the line 5—5 of Fig. 3.

The automatic feeding device is shown as used in connection with the metal melting

pot 10, of a typecasting machine, although the device can be used in connection with the melting pots of other machines for which the device is suitable, especially if the pot has a reciprocatory motion.

A vertical guide 11, preferably of tubular form, is supported above the pot 10, for the downward movement therein by gravity of the pigs 12 of metal or other material to be delivered to the pot for maintaining the level of molten metal or material in the pot. Said pigs are preferably of cylindrical form, and may be of any suitable dimensions.

The guide 11 is supported from the frame or body of the machine. Thus, said guide 11 is formed with a laterally projecting bracket 13 extending slidably through a block 14 and secured in adjusted position in said block by means of a set screw 15 carried by the block. Said block 14 is slidable vertically on a post 16 of a base clamp 17 that engages a member 18 of the frame, and the clamp has a set screw 19 to secure said clamp to the frame. The post 16 is thus rigidly secured to the frame of the machine, for supporting the block 14 in the desired vertical position, said block having a set screw 20 for clamping the block on the post. When the set screw 15 is loosened the bracket 13 can be slid horizontally in the block 14. The several adjustments enable the guide 11 to be properly positioned over the pot 10 so as not to interfere with the reciprocatory motion of the pot or any of the working parts.

The lower end of the guide 11 terminates above the molten material in the pot, but said guide has a tongue 21 projecting downwardly therefrom into the molten material in the pot and provided with an inwardly extending stop 22 to limit the downward movement of the pig into the pot so as to prevent the pig from striking the pot or any portion thereof when the pig gravitates in the guide 11.

A dog or catch 23 is provided to grip the pig and support it in the guide while the lower portion of the pig which is submerged in the molten material in the pot is melted away, said dog or catch being located below the lower end of the guide 11 but above the level of the molten material in the pot. The dog 23 is of U-shape so as to straddle the pig opposite to the tongue 21, with the terminals of said dog extended

upwardly, as at 24, and pivoted, as at 25, to a lug 26 with which the guide 11 is provided at one side near its lower end. The bend or loop of the dog 23 has a sharp edge 27 to bite the pig opposite to the tongue 21, and an arm 28 projecting from the dog 23 is pivotally connected, as at 29, to the lower terminal of a vertical rod 30 which has its upper terminal slidable through an apertured lug 31 projecting from the guide 11. A coil spring 32 surrounds the rod 30 and is confined between the lug 31 and a collar 33 secured on the rod, whereby said spring forcibly swings the dog or catch 23 downwardly to grip or clamp the pig 12 against the tongue 21.

Tripping means is provided for raising the rod 30 and dog 23 so as to remove the biting edge 27 from the pig, in order that the pig can slide downwardly by gravity until it strikes the stop 22. Thus, a rock shaft 34 is journaled in lugs 35 projecting from the guide 11 below the lug 21, and a slotted arm or tappet 36 is secured on the shaft 34 between the lugs 35 and straddles the rod 30 immediately below the collar 33. The butt end 37 of the arm 36 is formed to abut the guide 11 and limit the downward swinging movement of said arm, although the arm can swing upwardly to raise the collar 33 and rod 30. A pin or arm 38 is secured to one terminal of the shaft 34 and is connected by a light coiled spring 39 with the bracket 13, to hold the arm 36 yielding in its lowermost position. A downwardly extending arm 40 is secured to the opposite terminal of the shaft 34 and has an outstanding pointed lug 41 for the engagement of the tripper 42.

The tripper 42 has a lower notch 43 near its free end forming a hook or abutment 44 to engage over the upper sharp end of the lug 41 of the trip arm 40. The tripper 42 is pivoted, as at 45, on an angular supporting member 46 secured on the jacket of the pot 10, as clearly seen in Fig. 1. A hollow metal float 47 is disposed within the pot to float on the molten material, and is screw-threaded on the lower terminal of a rod 48 that slides through apertured ears 49 projecting from the member 46. An adjusting cap 50 is screw threaded on the upper terminal of the rod 48, and carries a set screw 51 to maintain the adjustment. The tripper 42 rests on the cap 50, so that the tripper is raised and lowered with the float 47 that rises and lowers with the level of the molten material in the pot.

When the pot 10 reciprocates in the horizontal direction as usual, the member 46 moves with the pot, so that the float 47 and tripper 42 also move with the pot. The free terminal of the tripper 42 is moved over the lug 41 and retracted by the back and forth movement of the pot, and it will be noted

that the guide 11 and pig or pigs therein are supported from the frame of the machine, so as not to burden the pot 10 with additional weight or strain, the member 46, float 47, tripper 42 and corresponding parts 70 being light in weight and being the only parts of the device which are mounted to move with the pot.

In operation, when the level of the molten material in the pot is lowered by the discharge of material from the pot, the float 47 moves downwardly accordingly, thereby permitting the tripper 42 to swing downwardly. Then as the pot reciprocates should the tripper 42 move downwardly sufficiently 80 the hook or abutment 44 will engage over the lug 41, when the level of the material in the pot reaches a predetermined low point. During the meantime, the portion of the pig 12 that is submerged in the molten material 85 in the pot is melted away, so that the lower end of the solid metal is now at the level of the molten material above the stop 22. When the tripper 42 engages over the lug 41, as aforesaid, and the pot 10 is returned 90 so as to move the tripper 42 away from the guide 11, the trip arm 40 is swung, inasmuch as the lug 41 is pulled with the hook 44. This will swing the shaft 34 and raise the 95 arm 36. Said arm 36 contacts with and raises the collar 33, thereby raising the rod 30 and dog or catch 23 against the influence of the spring 32. The dog or catch therefore releases the pig or solid metal and such pig will move down by gravity until it strikes the stop 22. This will raise the level 100 of the molten material in the pot, and the float 47 being raised will lift the tripper 42 so that it will be disengaged from the arm 40. Thus, when the tripper 42 is moved with 105 the pot toward the guide 11, the hook 44 will move farther than the lug 41, the movement of the arm 40 being limited by the contact of the arm 36 with the guide 11, as seen in Fig. 5, so that the tripper 42 can 110 be readily disengaged from the lug 41 under the influence of the float 47. The spring 32 now again depresses the dog or catch 23 so that it grips and holds the pig while the 115 portion of the pig below the level of the molten material is melted away. This operation is repeated whenever the level of the molten material in the pot recedes to a predetermined low level, and the supply of solid metal or material is thus automatically fed 120 into the pot, in order to eliminate the necessity for manually filling the pot. The only attention required is the placing of the metal pigs in the guide 11.

Having thus described the invention, what 125 is claimed as new is:—

1. The combination with a fixed support and a melting pot having a reciprocatory motion relatively to said support, of means for guiding solid material downwardly by 130

- gravity into said pot and supported by said support so as not to move with the pot, means engageable with the solid material to prevent its movement into the pot, the 5 solid material being movable downwardly by gravity into the pot when the second-named means is disengaged therefrom, a tripper mounted on the pot to move therewith and cooperable with the second-named 10 means in a predetermined position of the tripper to operate the second-named means to disengage it from the solid material, and means controlling said tripper according to the level of the molten material in the pot.
- 15 2. In a device of the character described, a guide for solid material, a U-shaped catch below the lower end of said guide to engage and support the material and having its terminals pivotally connected with the 20 guide, and means for swinging said catch to engage and disengage the material.
- 25 3. In a device of the character described, a guide for solid material, a catch to engage and support said material, a slidable rod connected to said catch, spring means for moving the rod in one direction to engage the catch with the material, and actuating means for moving the rod in the opposite direction to disengage the catch from the 30 material.
- 35 4. In a device of the character described, a guide for solid material, a catch pivotally connected with the guide and engageable with said material to support it in the guide, a rod slidably connected with said catch, a rocking trip member carried by the
- guide and operably connected with said rod for moving the rod to release the catch from the solid material, and a tripper for 40 tripping said trip member.
5. In a device of the character described, a vertical guide for solid material, a catch to engage the material at the lower end of the guide and pivotally connected with the 45 guide, a vertical rod pivotally connected with said catch and slidably connected with the guide, a collar on the rod, a spring for moving said rod to engage the catch with the material, a rock shaft carried by the 50 guide and having an arm to contact with said collar and move the rod to disengage the catch from the material, a trip arm carried by said shaft, and a tripper engageable with said trip arm. 55
6. The combination with a fixed support and a melting pot having a reciprocatory motion relatively to said support, of means for guiding solid material downwardly by gravity into said pot and supported by said support to relieve the pot of the weight of said means and solid material, means engageable with the solid material to prevent its movement into the pot, the solid material being movable downwardly by gravity into the pot when the second-named means is disengaged therefrom, and means for operating the second-named means by the movement of the pot and controlled by the 60 level of the molten material in the pot. 65
- In testimony whereof we hereunto affix our signatures.
- BENJAMIN R. TURNER.
